US0D1068625S

(12) **United States Design Patent** (10) **Patent No.:** **US D1,068,625 S**
(45) **Date of Patent:** **** Apr. 1, 2025**

(54) **BIKE CARRIER**

(71) Applicant: **Ningbo Innrack Technology Co., Ltd.**, Ningbo (CN)

(72) Inventor: **Yufeng Wang**, Ningbo (CN)

(73) Assignee: **Ningbo Innrack Technology Co., Ltd.**, Ningbo (CN)

(**) Term: **15 Years**

(21) Appl. No.: **29/964,266**

(22) Filed: **Sep. 23, 2024**

(51) LOC (15) Cl. **12-11**

(52) U.S. Cl.

USPC **D12/407**

(58) **Field of Classification Search**

USPC **D12/115, 406-408, 412, 414**
CPC .. B60R 9/06; B60R 9/10; B60R 9/045; B60R 9/048

(57) **CLAIM**

The ornamental design for a bike carrier, as shown and described.

DESCRIPTION

FIG. 1 is a front perspective view of a bike carrier, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is the bike carrier in a state; and,

FIG. 10 is an enlarged detail view of area 10 in FIG. 1.

The broken lines in the drawings illustrate the portions of the bike carrier, which form no part of the claimed design.

The dash-dot-dash broken lines encircling the enlarged views are for annotative purposes only and form no part of the claim thereof.

1 Claim, 10 Drawing Sheets
